CARD-HOLDING AND DISPLAYING TABLE COVER

Loretta Slack, Toronto, Ontario, Canada

Application December 13, 1956, Serial No. 44,186

Term of patent 14 years

(Cl. D34—13)

FIG. 1.

FIG. 2.

FIG. 3.

FIG. 4.

Fig. 1 is an upper corner perspective of the card-holding and displaying table cover showing my design in mounted position;

Fig. 2 is a reduced size top plan view;

Fig. 3 is a bottom plan view; and

Fig. 4 is a side elevational view of Fig. 2, drawn to a somewhat larger scale.

I claim:

The ornamental design for a card-holding and displaying table cover, substantially as shown.
